UNITED STATES PATENT OFFICE.

NICHOLAS R. SHULTS, OF LAKE CITY, MICHIGAN.

SECURING APPLIANCE FOR LINOLEUM, &c.

1,114,194.

Specification of Letters Patent. Patented Oct. 20, 1914.

Application filed June 17, 1914. Serial No. 845,701.

To all whom it may concern:

Be it known that I, NICHOLAS R. SHULTS, a citizen of the United States, residing at Lake City, in the county of Missaukee and 5 State of Michigan, have invented certain new and useful Improvements in Securing Appliances for Linoleum, &c.; and I do hereby declare the following to be a full, clear, and exact description of the invention, 10 such as will enable others skilled in the art to which it appertains to make and use the same.

My invention relates to a securing device for linoleum, etc.

15 My object is to produce a device that will securely hold the linoleum to the floor and yet allow it to creep or move as it expands or contracts, thus preventing it from buckling or tearing.

20 The drawings herewith are made part of this application in which—

Figure 1 is a perspective view of my securing device showing the top surface thereof. Fig. 2 is a cross section showing the 25 securing device in place between two pieces of linoleum. Fig. 3 is a side elevation of a securing device in place. Fig. 4 is a perspective view showing the under surface thereof.

30 In the detailed description of my invention reference is had to the inclosed drawings, and numerals are used to indicate the various parts, the same numeral being used to indicate the same part throughout.

35 My invention consists of a strip of metal 1 folded on itself to form a rib 2 longitudinally along its center and extending at right angles to the plane thereof. A plurality of anchoring triangular points 3 are struck up 40 from the surface of the strip and rib, alternately on either side of the rib and are located upon the edge thereof, extending in the same direction as the rib and forming an extension thereof. All parts of the 45 fastener are formed integrally from one piece of metal.

In operation the securing device is placed on top of two abutting pieces of linoleum with the rib and points extending downwardly in the joint. The device is then secured in place by driving the points into the floor, the body portion of the strip overlapping the linoleum on either side of the joint and the edge of the rib resting on the floor, thus securing the meeting edges and holding 55 the linoleum in place.

I have provided an efficient and cheap device for the purpose set forth and believing that the construction, advantages and manner of using my invention have thus been 60 made clearly apparent, further description is deemed unnecessary.

What I desire to secure by Letters Patent is:

1. A securing device consisting of a strip 65 of metal, having a longitudinal rib adapted to fit between the abutted edges of the linoleum or like floor covering and having a plurality of anchoring points carried by the rib and adapted to be driven into the 70 floor.

2. A securing device consisting of a strip of metal; a rib formed of folds of said strip of metal and a plurality of points struck up from the rib and the adjacent body portion 75 of the strip, and located on the edge of the said rib, whereby the securing device is fastened to the floor.

3. A securing device having a body portion folded to form integrally a central rib, 80 and sharp points struck up from the said body portion and adjacent part of the rib forming an extension thereof.

In testimony whereof I have signed my name to this specification in the presence of 85 two subscribing witnesses.

NICHOLAS R. SHULTS.
